H. JULIUS SMITH, OF BOSTON, MASSACHUSETTS.

Letters Patent No. 96,045, dated October 19, 1869.

IMPROVED MODE FOR ATTACHING DIAMONDS FOR STONE-DRILLING.

The Schedule referred to in these Letters Patent and making part of the same

To all whom it may concern:

Be it known that I, H. JULIUS SMITH, of Boston, in the county of Suffolk, and State of Massachusetts, have invented a new and improved Mode of Setting or Fixing Diamonds in Drill-Heads and other Tools; and I do hereby declare the following to be a full and correct description of the same, reference being had to the accompanying drawings, in which—

Figure 1 is a vertical section of a drill-head, with a diamond set in it in the mode which I use.

In the drawing—

- A marks the drill-head;
- B, the bore for the reception of the setting;
- C, the metallic setting; and
- D, the diamond.

The setting C is screwed into the bore B, which is threaded to receive it.

The diamond is attached and firmly embedded in the metal, by having the metal cast around it under pressure.

The ordinary mode of attaching diamonds to drills, and other tools, is by forcing the metal around them, by means of a punch. This method fails to insure perfect contact, in every part, between the metal and the diamond; and the latter soon becomes loose, and falls out.

If a number of diamonds are inserted near each other, as is frequently the case, the one that first becomes loose is liable to crush or break out the others, or some of them.

The common method, moreover, is slower and more expensive than that which I adopt.

I prefer to attach the diamonds to small plugs or settings, as C, for greater convenience in inserting and removing them from the heads in which they are de-

signed to be used; but they can be inserted singly, or in any desired number, by casting the drill-head or tool directly around them, if preferred. I have essayed both methods.

Steel, chilled, iron, brass, or other metal, may be used, as may be found most desirable; and diamonds set in this way can be used for the cutting or grinding-points or surfaces of saws, drills, and stone-dressing or turning tools.

The casting is done in moulds of pipe-clay, the diamonds being held in position in any convenient mode.

The pressure is produced by a piston and screw.

The mode of performing the casting, or effecting the pressure, forms no part of my invention.

Having thus fully described my invention,

What I claim, and desire to secure by Letters Patent, is—

1. A diamond-drill, or other tool, in which one or more diamonds are attached to the metallic head or stock, by casting the metal, under pressure, upon or around the diamonds, so that they shall be firmly embedded and held in the metal, as described.

2. A drill, or other tool, formed by setting or embedding single diamonds in separate plugs or settings of metal, in the manner described, and screwing or otherwise inserting and fixing such plugs in the drill-head, or tool, substantially as specified.

The above specification of my said invention signed and witnessed at Boston, this 17th day of August, A. D. 1869.

H. JULIUS SMITH.
